Primary Examiner — Mary Ann Calabrese(74) *Attorney, Agent, or Firm* — Gabriel & Palaez, PLLC; Michael G. Gabriel(57) **CLAIM**

The ornamental design for a pillowcase, as shown.

DESCRIPTION

FIG. 1 is a perspective view of the pillowcase of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an alternate perspective view of the invention with an unclaimed pillow inserted;

FIG. 9 is an alternate front view thereof;

FIG. 10 is an alternate rear view thereof;

FIG. 11 is an alternate left side view thereof;

FIG. 12 is an alternate right side view thereof;

FIG. 13 is an alternate top view thereof;

FIG. 14 is an alternate bottom view thereof; and,

FIG. 15 is a partial front elevation view thereof.

In the drawings, the broken lines illustrate environment and form no part of the claimed design.
